PICTURE TRANSMISSION APPARATUS

Gregory N. Ogleblinsky, deceased, late of Collingswood, N. J., by Vladimir K. Zworykin, administrator, Philadelphia, Pa., assignor to Radio Corporation of America, a corporation of Delaware.

Application September 28, 1935, Serial No. 42,657

12 Claims. (Cl. 178—7.2)

The invention relates to picture transmission apparatus and particularly to cathode ray tubes designed to generate picture signals.

5 An object of the invention is to provide an improved method of and means for producing picture signals.

10 A further object of the invention is to provide an improved method of and means for taking picture signals from elements of a mosaic structure or the like.

15 A further object of the invention is to provide an improved means for utilizing the phenomenon of secondary electron emission in producing picture signals.

20 A still further object of the invention is to provide an improved method of and means for utilizing the phenomenon of secondary electron emission in picture transmitting tubes or the like.

25 A still further object of the invention is to provide an improved cathode ray picture transmitter tube and/or associated circuit.

Other objects, features and advantages of the invention will appear from the following description taken in connection with the accompanying drawings in which

30 Figure 1 is a schematic and circuit diagram of one embodiment of the invention;

35 Figure 2 is a perspective view of certain electrode structure shown in Figure 1;

40 Figure 2a is a view taken in cross section on Figure 2;

45 Figure 3 is a schematic and circuit diagram of another embodiment of the invention;

50 Figure 4 is a perspective view of certain electrode structure shown in Figure 3;

55 Figure 5 is a schematic and circuit diagram of still another embodiment of the invention; and

60 Figure 6 is a perspective view of certain electrode structure shown in Figure 5.

Referring to Figure 1 there is shown a cathode ray transmitter tube comprising a highly evacuated envelope 1 having an electron gun therein, consisting of an indirectly heated cathode 2, a control electrode 3 and a first anode 4. A second anode 6 is provided for electrostatically focusing the cathode ray. It is usually preferred to maintain the second anode 6 at a higher positive potential than the first anode 4 in order to further accelerate the electrons. However, as indicated on the drawings, the second anode 6 may be at a lower potential than the first anode and good focusing of the electron beam obtained by properly selecting the ratio of anode voltages. A direct current voltage may be applied to the anode 4 from any suitable source, such as a bat-

tery 7, while the second anode 6 is maintained at ground potential. The control electrode 3 may be maintained at the same potential as the cathode 2.

Preferably, a portion of the inner surface of the envelope 1 is provided with a metallic coating 8 which is connected to ground whereby it is maintained at the same potential as the second anode. This arrangement prevents the deflecting coils 9 from inducing interfering signals into the picture signal output circuit.

Any suitable means such as a pair of deflecting coils 9 is provided for deflecting the cathode ray in a direction at right angles to the plane of the paper.

15 The electrode structure which is scanned by the cathode ray for the purpose of producing picture signals and which is shown more clearly in Figures 2 and 2a includes a large number of metallic pins 11, nickel pins for example, which 20 are mounted in any suitable insulating support such as a glass block 12. It will be noted that the pins 11 are insulated from each other and do not have any direct current connection to any part of the tube structure or circuit. Each pin 25 corresponds to a picture element of the picture being transmitted, there being, of course, a much larger number of pins in an actual embodiment of the invention than indicated on the drawings.

20 In front of the pins 11 and supported from 30 the glass block 12 there is a collector electrode 13 which in the particular embodiment illustrated is a conductor bent into the shape of a rectangle. Instead of being in this particular form, the collector electrode 13 may be in the 35 form of a plate having a slit-like opening cut therein.

25 In front of the collector electrode 13 and supported from the glass block 12 there is a shield 14 which preferably is of conducting material 40 which is maintained at ground potential by means of a suitable connection 16.

30 In the shield 14 opposite each pin 11 there is an opening 17 of such size as to permit the passage of the cathode ray therethrough to strike 45 the pin 11 and at the same time to prevent the cathode ray from striking the collector electrode 13. It will be evident that as the cathode ray is deflected along the row of pins 11 it passes through the openings 17 to strike the pins successively without striking the collector electrode 13. As each pin 11 is struck by the cathode ray, it emits secondary electrons which are collected by the electrode 13, as will be more completely described hereinafter.

Opposite the back side of the pins 11 there is mounted a photosensitive screen 18. This screen may be a fine screen of nickel wire, for example, which is silver plated and treated with caesium in a well known manner to make it photosensitive. In the embodiment illustrated in Figure 1 the photosensitive screen 18 is maintained at a negative potential with respect to ground by a battery 19.

10 The collector electrode 13 is connected through an output resistor 21 to ground as indicated on the drawings or it may be made either slightly positive or slightly negative with respect to ground by adjusting the tap 22 on the battery

15 23. Voltage variations appearing across the output resistor 21 are impressed upon the input circuit of a suitable amplifier 24.

The apparatus above described is suitable for transmitting pictures from a motion-picture film indicated at 26. In front of the film 26 there is a shield 27 having a narrow slit 28 extending across the width of the film and parallel to the row of pins 11. The film 26 is illuminated by light passing through suitable condensing lenses 29 and an image of the picture at the slit 28 is projected upon the photosensitive screen 18 by means of a suitable optical system indicated at 31.

Vertical scanning of the picture is effected by 30 running the picture film 26 continuously while the cathode ray is being deflected horizontally and at right angles to the movement of the film. It has been found that the secondary electrons emitted by the pins 11 vary in accordance with 35 the shading of the picture elements. Therefore the signal appearing in the output of the amplifier 24 is a picture signal which may be transmitted to reproduce the picture at a suitable picture or television receiver. It is believed that 40 the operation of the transmitter tube is substantially as follows:

The image of the picture projected upon the photosensitive screen causes the screen to emit photo-electrons depending in number upon the 45 intensity of light at a particular point on the screen. Thus, a pin opposite a brightly lighted point on the screen will receive more photo-electrons than a pin opposite a dimly illuminated point and it will become more negatively charged. 50 As each pin is bombarded by the electrons from the cathode ray it will emit secondary electrons which will move over to the collector electrode. The number of secondary electrons which will move over to the collector electrode will depend 55 upon the potential difference between the pin and the collector electrode. Therefore, if the collector electrode is at ground potential, for example, the more negative a pin the greater will be the number of secondary electrons moving over to the 60 electrode. This variation in the number of secondary electrons reaching the collector electrode is, of course, the picture current and represents a positive picture.

As will be more clearly understood from the 65 description of the circuit shown in Figure 3 which follows, the screen 18 may be maintained at a positive potential with respect to ground providing the ends of the pins which face the screen are made photosensitive. In that case, 70 there is no object in having the screen itself photosensitive.

In Figure 3 the tube structure, except for the pin or mosaic structure and associated electrodes, is substantially the same as shown in Figure 1, 75 like parts in the two figures being indicated by

the same reference numerals. In this transmitting tube, as in the tube shown in Figure 1, only one row of pins 32 is employed since the picture which is to be transmitted is on a continuously moving film 26. The metal pins 32 are supported by glass beads 33 which are inserted in the cells of a honeycomb structure 34 of nickel or the like. Preferably the pins 32 extend beyond the honeycomb structure 34 both at the front and at the back. It has been found that in some cases improved results may be obtained if mica sheets 36 and 37 are placed at the front and back of the honeycomb structure, respectively, with the pins 32 extending therethrough.

A collector electrode 38 is positioned in front of the pins 32, this collector taking the form of a metallic plate having an opening 39 therein opposite each pin. A metallic shielding electrode 41 is positioned in front of the collector electrode 38, the shielding electrode having a row of openings 42 therein each of which is positioned in line with a pin and its corresponding opening 39 in the collector electrode. The openings 42 in the shielding electrode 41 are smaller than the openings 39 in the collector electrode whereby electrons in the main electron beam or cathode ray may pass through the openings in the shielding electrode 41 to the pins 32 without striking the collector electrode 38. Thus, as in the structure shown in Figure 1 only the secondary electrons from the pins 32 reach the collector electrode 38.

The collector electrode 38 is preferably connected through an output resistor 43 to ground whereby picture signals may be taken off the resistor 43 by means of any suitable amplifier 44.

As in the case of the apparatus shown in Figure 1, a photosensitive screen 46 may be positioned on the back side of the pins 32 and maintained at a negative potential with respect to ground by means of a battery 47. When operated in this way, the screen 46 may have a negative potential of from -10 volts to -70 volts. Preferably, however, the ends of the pins 32 facing the screen 46 are made photosensitive while the screen is merely a metallic screen which is not photosensitive. In this case, the screen 46 is maintained at a positive potential with respect to ground and acts as a collector of photo-electrons. The positive screen potential is not critical, potentials of from 45 volts to 100 volts having been found satisfactory.

In the case of the preferred embodiment just described, the operation is substantially as follows:

An image of the picture at the slit 28 is projected upon the photosensitive ends of the pins 32 whereby they emit more or less photo-electrons depending upon the shading of the picture elements. The more electrons emitted by a pin, the more positive it becomes. Therefore, the number of secondary electrons which pass from each pin to the collector electrode 38 depends upon the shading of the picture elements and the flow of current through the output resistor 43 is the picture signal which represents a negative picture.

In the embodiment of the invention shown in Figure 5, the tube structure for generating the cathode ray is the same as that shown in Figure 1. In the two figures like parts are indicated by the same reference numerals.

In the specific embodiment of the invention shown in Figure 5, instead of employing a single line of pins, a complete mosaic of pins is em

ployed whereby an outdoor scene or the like may be picked up by a camera and the picture transmitted by projecting the image upon a photo-sensitive screen or upon the ends of the pins which have been made photosensitive.

5 The mosaic pin structure, which is also shown in Figure 6, comprises a honeycomb structure 51 which may be made from nickel ribbon, glass beads 52 which are inserted in the honeycomb openings, and metallic pins 53 which are supported in the glass beads 52. The construction of this honeycomb mosaic is substantially the same as that of the honeycomb structure shown in Figure 4.

15 In front of the mosaic pins 53 are positioned collector and shielding plates 54 and 56, respectively, the collector plate 54 having comparatively large openings therein which are located opposite the pins 53. The shielding plate 56 has a corresponding number of smaller openings which are positioned opposite the collector plate openings and in line with these openings and the pins. The collector plate 54 and shielding plate 56 correspond to the collector and shielding electrodes 25 38 and 42, respectively, shown in Figures 3 and 4, and their functions are the same.

The honeycomb structure 51 and the shielding plate 56 are preferably connected to the metallic coating 8 and to ground. The collector plate or 30 electrode 54 is connected through an output resistor 57 either directly to ground or through a battery 58 inserted for the purpose of maintaining the collector electrode positive with respect to ground. Picture signal is taken off the output 35 resistor 57 by means of the amplifier 59.

If desired, the ends of the pins 53 on the back side of the mosaic may be made photosensitive and a positive screen for collecting photo-electrons placed adjacent thereto whereby the 40 tube may be operated as described in connection with Figure 3. In that case, an image of the picture to be transmitted is projected upon the light-sensitive ends of the pins.

In the particular embodiment illustrated, however, a photosensitive screen 61 is placed opposite the back side of the mosaic whereby an image of the picture 62 to be transmitted may be projected thereon to release photo-electrons. The structure of this screen may be the same as that 45 of the screen 18 shown in Figure 1. A fine mesh metallic screen 63 is positioned between the mosaic and the photosensitive screen 61 and maintained at a positive potential with respect to the photosensitive screen by means of a battery 64 or the like, for the purpose of accelerating the photo-electrons and projecting them towards the mosaic. Since the photosensitive screen 61 is located some distance from the mosaic, a magnetic focusing coil 66 is provided which causes the 50 photo-electrons leaving a particular point on the photosensitive screen 61 to move over to a corresponding point on the mosaic.

If desired, the accelerating screen 63 and the focusing coil 66 may be omitted and the photo-sensitive screen 61 placed so close to the mosaic that focusing of the photo-electrons is unnecessary.

In the several embodiments of the invention described above the electron beam velocity is not critical. A beam velocity of from 200 volts to 500 volts was found to be satisfactory.

From the foregoing description it will be apparent that various other modifications may be made in the invention without departing from the spirit and scope thereof and it is desired

therefore that only such limitations shall be imposed thereon as are necessitated by the prior art and set forth in the appended claims.

What is claimed is:

1. In a transmitter tube, means for generating a beam of electrons, a mosaic of elements each electrically insulated whereby it may receive and retain a charge and each adapted to emit secondary electrons, means for causing each of said elements to receive a charge corresponding to the shading of a picture element, means for causing said beam to scan said elements whereby secondary electrons are emitted, and means including a collector electrode positioned out of the path of said beam for collecting said secondary electrons and supplying them to a picture signal circuit. 5

2. The invention according to claim 1 characterized in that said collector electrode has at least one opening therein, said electrode being positioned out of the region traversed by said beam and being so positioned that said beam passes through said opening to strike at least one of said elements. 10 20

3. In an electron tube, means for generating a beam of electrons, a mosaic of elements each electrically insulated whereby it may receive and retain a charge and each adapted to emit secondary electrons, means for causing each of said elements to receive a charge corresponding to the shading of a picture element, means for causing said beam to scan said elements whereby secondary electrons are emitted, an electrode positioned to be bombarded by said secondary electrons but not by the electrons in said beam, and a signal output device connected between said electrode and ground. 25 30 35

4. In an electron tube, a plurality of elements each adapted to receive an electric charge corresponding to the shading of a picture element and each adapted to emit secondary electrons, means for causing said elements to receive said charges, means for generating a beam of electrons and directing it towards said elements, said beam generating means including an electrostatic focusing electrode, means for deflecting said beam and causing it to scan said elements whereby secondary electrons are emitted, and means including a collecting electrode out of the path of said beam for collecting said secondary electrons and supplying them to a utilization circuit. 40 45 50

5. The invention according to claim 4 characterized in that said focusing electrode is connected to ground.

6. The invention according to claim 4 characterized in that shielding means is provided between said beam deflecting means and said elements, said shielding means being in the form of a metallic coating on the inner surface of the electron tube envelope and being connected to ground. 55 60

7. In an electron tube, means for generating a beam of electrons, a mosaic of elements each electrically insulated whereby it may receive and retain a charge and each adapted to emit secondary electrons, means for causing each of said elements to receive a charge corresponding to the shading of a picture element, means for scanning said elements by said beam and thereby producing secondary electrons which vary in quantity in accordance with said charges, an electrode for collecting said last mentioned secondary electrons, and an output impedance unit connected between said collecting means and ground. 65 70 75

8. In a transmitter tube, means for generating a beam of electrons, said means including an elec- 75

- 6 electrostatic focusing electrode, a plurality of ele-
7 ments each adapted to receive an electric charge
8 corresponding to the shading of a picture ele-
9 ment and each adapted to emit secondary elec-
10 trons, means for causing said elements to receive
11 said charges, means for causing said beam to scan
12 said elements whereby secondary electrons are
13 emitted, and means for collecting said secondary
14 electrons and supplying them to a picture signal
15 output circuit, said collecting means comprising
16 an electrode having an opening therein, said elec-
17 trode being positioned between said beam gener-
18 ating means and said elements and out of the
19 path of said beam whereby the beam passes
20 through said opening.
- 15 9. The invention according to claim 8 charac-
21 terized in that said electrode is substantially in
22 the form of a ring.
10. In a transmitter tube, means for generating
23 a beam of electrons, at least one row of elements,
24 each element being adapted to receive a charge
25 corresponding to the shading of a picture ele-
26 ment and each adapted to emit secondary elec-
27 trons, means for projecting an image of said
28 picture toward the back side of said elements,
29 means including an electrode positioned between
30 said elements and said projecting means for caus-
31 ing each element to receive a charge correspond-
32 ing to said shading, means for causing said beam
33 to scan the front side of said elements whereby
34 they emit secondary electrons, means for collect-
35 ing said electrons and supplying them to a picture
36 signal circuit, said collecting means comprising
37 a collector electrode positioned adjacent to the
38 front side of said pins, and a shielding element
39 so positioned between said beam generating
40 means and said collector electrode that the beam
41 is prevented from striking the collector electrode.
11. In combination, means for producing a
- beam of electrons, a mosaic of elements each
5 adapted to receive a charge and adapted to emit
secondary electrons, a photosensitive screen,
means for projecting an optical image upon said
screen whereby photo-electrons are released, an
acceleration screen positioned between said pho-
6 to tonsensitive screen and said mosaic, means for
7 maintaining said accelerating screen positive
8 with respect to said photosensitive screen whereby
9 said photo-electrons are projected against the
10 back side of said mosaic, means for establishing
11 a focusing field between said mosaic and said
12 accelerating electrode such that photo-electrons
13 leaving points on said photosensitive screen reach
14 corresponding points on said mosaic, means for
15 scanning said mosaic on the front side by said
16 beam, whereby said elements emit secondary
17 electrons, and means for collecting said second-
18 ary electrons and supplying them to a picture
19 circuit.
12. In combination, means for generating a
20 beam of electrons, a mosaic of elements each
21 electrically insulated whereby it may receive and
22 retain a charge and each adapted to emit sec-
23 ondary electrons, means for causing each of said
24 elements to receive a charge corresponding to the
25 shading of a picture element, means for causing
26 said beam to scan said elements whereby sec-
27 ondary electrons are emitted, an electrode posi-
28 tioned adjacent to said elements and out of the
29 region traversed by said beam whereby it collects
30 said secondary electrons, a connection between
31 said electrode and ground, said connection in-
32 cluding an impedance unit, an amplifier tube
33 having an input circuit, and means for coupling
34 said input circuit across said impedance unit.
